UNITED STATES PATENT OFFICE.

HATTIE GREENE, OF RICHMOND, INDIANA.

HEAD-REST.

No. 906,410.

Specification of Letters Patent.

Patented Dec. 8, 1908.

Application filed April 24, 1908. Serial No. 429,089.

To all whom it may concern:

Be it known that I, HATTIE GREENE, a citizen of the United States of America, residing at Richmond, in the county of Wayne 5 and State of Indiana, have invented new and useful Improvements in Head - Rests, of which the following is a specification.

This invention relates to head rests designed for use in shampooing and washing 10 the hair, and one of the principal objects of the same is to provide a head rest which can be quickly attached to a stationary wash bowl for thoroughly rinsing and washing the hair without the liability of splattering or 15 wetting the clothes of the person being treated.

Another object of the invention is to provide a simple and efficient device for resting the head during the operation of rinsing the hair after it has been shampooed, the construction of the device being such that either 20 the back of the head may be supported upon the rest or the forehead of the person supported upon the rest in position so as to not 25 interfere with breathing during the operation.

These and other objects may be attained by means of the construction illustrated in the accompanying drawing, in which,— 30 Figure 1 is a perspective view of a head rest made in accordance with my invention, said head rest being shown in use and attached to a stationary washstand. Fig. 2 is a perspective view looking at the front of the 35 head rest. Fig. 3 is a plan view of the same. Fig. 4 is a side view of the head rest, a portion of the washstand being shown in section.

Referring to the drawings for a more specific description of my invention, the numeral 40 1 designates an ordinary stationary washstand to which my head rest may be secured. The head rest consists of a catch basin 2 provided with a marginal flange 3 which extends partially around the same and is omitted at 45 the point 4 to permit the water to run off. This catch basin has a central recess 5 in the front portion thereof and is rounded at the outer edge, as at 6. This catch basin is sup-

ported upon a base 7 in an inclined position, said base having end lugs 8 engaged by suitable clamps 9 for holding the device firmly in place upon the washstand. Supported upon suitable legs 10 secured at their lower ends to the basin 2 is a padded rest 11 of curved formation in which the person being treated 50 55 may rest the head either upon the neck portion or upon the forehead.

The operation of my head rest may be briefly described as follows: After the hair has been thoroughly cleaned the head is 60 thrown back upon the rest 11 and the hair thoroughly rinsed. Should it be necessary to get at the back of the head to rinse the hair the patient turns over and rests the forehead upon the rest 11, the cut-out portion 65 5 of the basin 2 permitting the mouth and nostrils free action.

From the foregoing it will be obvious that my invention is of a simple character, can be instantly clamped to a washstand ready for 70 use, is efficient for its purpose and can be manufactured at slight cost.

Having thus described the invention, what is claimed as new, is:—

1. A head rest comprising a support, a 75 curved catch basin mounted upon said support and provided with a marginal flange cut away at one portion, and a head rest rising from said basin.

2. A head rest for barbers' use comprising 80 a base portion adapted to be clamped to a stationary washstand, a curved catch basin, and a curved head rest above the catch basin.

3. A head rest for barbers' use comprising 85 a catch basin having a curved recess in one side thereof, a marginal flange extending partially around the same, and a head rest supported upon feet rising from said catch basin. 90

In testimony whereof I affix my signature in presence of two witnesses.

HATTIE GREENE.
